HERMAN E. LOEBE, OF JERSEY CITY, NEW JERSEY.

GAS-HEATER.

1,147,521.

Specification of Letters Patent. Patented July 20, 1915.

Application filed October 29, 1914. Serial No. 869,247.

To all whom it may concern:

Be it known that I, HERMAN E. LOEBE, a citizen of the United States, and a resident of Jersey City, in the county of Hudson and 5 State of New Jersey, have invented a new and Improved Gas-Heater, of which the following is a full, clear, and exact description.

The object of the invention is to provide a new and improved gas heater more especially designed for economically heating rooms with a minimum consumption of gas, and to allow of using the gas heater for heating water, or for cooking purposes, or 10 for use in ranges, hot air furnaces and the like.

In order to accomplish the desired result, use is made of an outer mantle closed at the bottom and having a chamber in the form of a frustum of a cone, the chamber having 15 outlet openings at the lower end, an inner mantle having its outer wall in the form of a frustum of a cone and its inner wall in the form of an inverted frustum of a cone, the said inner mantle being set in the lower 20 portion of the said chamber and being spaced from the outer mantle to form a passage between the mantles, the top of the inner mantle being a distance below the top of the said outer mantle, a burner at the 25 lower end of the said inner mantle, and means for opening and closing the top of the outer mantle.

A practical embodiment of the invention 30 is represented in the accompanying drawings forming a part of this specification, in which similar characters of reference indicate corresponding parts in all the views.

Figure 1 is a perspective view of the gas 35 heater; Fig. 2 is a sectional side elevation of the same; Fig. 3 is a plan view of the same; and Fig. 4 is a sectional plan view of the same on the line 4-4 of Fig. 2.

The gas heater is mounted on a stand 40 having a base A from which rises a pipe B provided with an air inlet B' and a gas inlet B² connected by a flexible tube or other means with a gas supply pipe or other source of gas supply. The upper end B³ of the pipe B forms a burner and from the 45 said upper end extend arms B⁴ in an upward and outward direction for supporting a flanged ring B⁵ in which is set a base plate C, preferably of asbestos, having a central opening C', and on this base plate C rests the lower end of an outer mantle D, prefer- 50 ably made of cast-iron. The outer mantle D is held against lateral movement by the flange of the ring B⁵, and the inner wall of the said mantle is in the form of a frustum of a cone to form a correspondingly shaped 55 chamber within the mantle, and the upper end of the outer mantle D is provided with an apertured top plate E having an apertured regulating disk F for opening and closing the openings in the top plate E whenever it is desired to do so. The regulator F is provided with a handle F' for conveniently turning it with a view to move its apertures in or out of register with the 60 apertures in the top plate E. The edge of the regulator F is provided with a notch F² into which projects a stop pin E' held on the top plate E and serving to limit the turning motion of the regulator F. Within 65 the lower portion of the outer mantle D is arranged an inner mantle G, preferably made of cast-iron, and resting on the base plate C. The outer wall of this inner mantle G is in the form of a frustum of a cone while the inner wall of the said mantle is 70 in the form of an inverted frustum of a cone, and the lower end of the opening G' of the said inner mantle G is in register with the central opening C' of the base plate C so that the flame emanating from 75 the burner B³ can pass through the openings C', G' and into the upper portion of the chamber formed by the outer mantle D. By reference to Fig. 2 it will be noticed 80 that the inner mantle G has its top a distance below the top of the outer mantle D, and the outer wall of the said mantle G is spaced from the inner wall of the mantle D to form a passage between the said mantles 85 to connect the upper portion of the interior of the mantle D with the outlet openings D' arranged near the lower end of the outer mantle D. By the arrangement described 90 the flame from the burner in passing through the inner mantle G heats the latter from the inside, and the flame passing into the upper portion of the mantle D heats the latter likewise from the inside, and then the heat in passing down through the passage 95 between the mantles heats the outside of the inner mantle G and the lower portion of the outer mantle D.

By the arrangement described, the mantles are quickly heated to a red heat and when this stage is reached the operator can 100 105 110

reduce the supply of gas by partly closing a valve not shown and with which the supply pipe B may be provided. The reduced flame is sufficient to keep the mantles in a 5 red hot condition. It is understood that the mantles are massive and hence when once heated to a red heat remain in this state by the use of a very much reduced flame. In practice, about one-half hour is required to 10 heat the mantles, say of an aggregate weight of seventeen pounds with a burner consuming gas worth about one cent an hour.

A large amount of air is drawn in with the flame through the opening C' and this 15 air is highly heated by the flame and by coming in contact with the heated mantles G and D so that the air finally passes out through the openings D' in a highly heated state. It will also be noticed that a large 20 amount of heat is radiated from the outer mantle D to its surroundings, and the top plate E and its regulator F are heated by the flame and hot air, the heat of the said plate being radiated into its surroundings. When 25 it is desired to allow the heated air to pass directly into the room, the regulator F is wholly or partly opened, thus diverting a large amount of heated air from the outlet openings D'.

30 In practice, the mantles D and G become readily hot and consequently the air passing through the mantles and drawn in by the flame is quickly heated and a large amount of heat is radiated into the room.

35 When starting the heat, the regulator F is opened to allow quick heating of the mantles, and when this has been done the regulator F is closed to cause the heated air to travel down in the narrow passage to and 40 out of the openings D'.

45 It will be noticed that by constructing the mantle G with an opening in the form of an inverted frustum of a cone, the entering flame and air can readily spread during its upward passage through the mantle G and thus the heated air passes into the upper portion of the outer mantle D to be forced downward therein into the narrow passage between the mantles before finally reaching 50 the outlet openings D'.

The heater is very simple and durable in construction, composed of comparatively few parts, and not liable to get out of order.

Having thus described my invention, I 55 claim as new and desire to secure by Letters Patent:

60 1. A heater, comprising a burner, a base plate having a central opening located above the said burner, an outside mantle held on the said base plate and provided at its lower portion with outlet openings, the said mantle having a chamber in the form of a frustum of a cone, a top plate held on the top of the said outer mantle and provided with 65 openings, a regulator mounted to turn on the

said top plate and having openings adapted to register with the said top plate openings, and an interior conical mantle set on the said base plate within the said outer mantle and spaced a short distance from the outer mantle 70 forming with the latter a narrow annular passage leading to the said outlet openings, the said inner mantle being of considerable less length than the outer mantle and having a central opening registering with the opening of the base plate. 75

2. A heater, comprising a stand having a burner and a support above the said burner, a base plate resting on the said support and having a central opening, an outer mantle 80 held on the said support and the said base plate, the outer mantle having a chamber in the form of a frustum of a cone, the lower end of the outer mantle having outlet openings leading from the said chamber, and an inner mantle set on the said base plate and extending within the said outer mantle, the inner mantle being of conical shape and having an opening therethrough in the form of an inverted frustum of a cone and in register 85 with the base plate opening, the said inner mantle being of a slightly less diameter than the chamber of the outer mantle and forming therewith a narrow annular passage, the top of the inner mantle being a 90 distance below the top of the said outer mantle. 95

3. A heater, comprising a tubular stand having at its lower end air and gas inlets and at its upper end a burner and upwardly and outwardly extending arms carrying a support above the said burner, a base plate resting on the said support and having a central opening, an outer mantle held on the said support and the said base plate, the outer mantle having a chamber in the form of a frustum of a cone, the lower end of the outer mantle having outlet openings leading from the said chamber, an inner mantle set on the said base plate and extending within the said outer mantle, the inner mantle being of conical shape and having an opening therethrough in the form of an inverted frustum of a cone and in register with the base plate opening, the said inner mantle 100 forming an annular passage with the said outer mantle and the top of the inner mantle being a distance below the top of the said outer mantle, an apertured top plate on the top of the said outer mantle, and a regulator mounted to turn on the said plate and having openings adapted to move into and out of register with the said top plate apertures on turning the said regulator. 115

4. A heater, comprising an outer mantle 125 of thick material, closed at the bottom and having a chamber in the form of a frustum of a cone, the chamber having outlet openings at the lower end, an inner mantle having its outer wall in the form of a frustum 130

of a cone and its inner wall in the form of an inverted frustum of a cone, the said inner mantle being also of thick material and set in the lower portion of the said chamber and 5 being spaced a short distance from the outer mantle to form a narrow passage between the mantles, the top of the inner mantle being a distance below the top of the said outer mantle, a burner at the lower end of

the said inner mantle, and means for opening and closing the top of the outer mantle. 10

In testimony whereof I have signed my name to this specification in the presence of two subscribing witnesses.

HERMAN E. LOEBE.
